DESIGN FOR A HANDBAG FRAME

Ida Jolles, New York, N. Y.

Application May 25, 1940, Serial No. 92,589

Term of patent 3½ years

To all whom it may concern:

Be it known that I, Ida Jolles, a citizen of the United States of America, residing in New York city, in the Borough of Manhattan, county and State of New York, have invented a new, original, and ornamental Design for a Handbag Frame, of which the following is a specification, reference being had to the accompanying drawing, forming part thereof, wherein:

I claim:

The ornamental design for a handbag frame, substantially as shown.

IDA JOLLES.
